[57] **CLAIM**

The ornamental design for an embossing tool, substantially as shown and described.

DESCRIPTION

FIG. 1 is a perspective view from the front, one side and above of an embossing tool showing my new design;
FIG. 2 is a perspective view from the rear, below and the other side thereof; and
FIG. 3 is a side elevation showing said one side.

FIG. 1.

FIG. 2.

FIG. 3.
